DISPENSING CONTAINER

Charles C. Morrison, New York, N. Y., assignor
to Continental Can Company, Inc., New York,
N. Y., a corporation of New York

Application June 22, 1938, Serial No. 215,274

8 Claims. (Cl. 221—62)

The present invention relates to new and useful improvements in dispensing containers, and more particularly to improvements in a dispensing container having a closure which is shiftable in opposite directions for opening or closing a dispensing opening in the container.

An object of the present invention is to provide a dispensing container of the above type, wherein the closure is resiliently maintained in contact with the adjacent surface of the container and is normally held in position for closing the dispensing opening.

A further object of the invention is to provide a dispensing container of the above type, wherein spring closing means are provided for normally forcing the closure from open to closed position.

A still further object of the invention is to provide a dispensing container of the above type, wherein the closure includes inner and outer closure members, one of which is adapted to house the spring closing means.

A still further object of the invention is to provide a dispensing container of the above type, wherein the inner closure member is in the form of a spring plate maintaining both closure members in contact with the adjacent surfaces of the container and wherein the outer closure member is recessed to house the spring closing means.

The above, and other objects of the invention will in part be obvious, and will be hereinafter more fully pointed out.

In the accompanying drawing,

Figure 1 is a top plan view showing the closure means in a closed position.

Figure 2 is a fragmentary side view of Figure 1, in section, showing the closure means.

Figure 3 is a view similar to Figure 2 showing a modified form of spring closing means.

Figure 4 is a top plan view of Figure 3 with the outer closure member removed.

Referring more in detail to the accompanying drawing, and particularly to Figures 1 and 2, the body portion 10 of the container is illustrated as being substantially oval in shape, but it is to be clearly understood that the container may be of any desired shape. The body portion is provided with a neck portion 11 which is integrally joined to the body portion by an outward bead 12. The container top 13 is provided with a depending flange 14 which fits over the neck portion 11 and abuts against the outward bead 12. It is to be clearly understood that the can top 13 may be secured to the body portion 10 in any suitable manner.

The container top is illustrated as being bowed

upwardly and is provided with an outwardly offset portion 15. The outwardly offset portion 15 is curved and forms an internal recess thereunder with the wall portion 16 between the offset portion 15 and the top 13 providing an internal shoulder. A part of the offset portion 15 is cut away to provide a longitudinal slot 17. A portion of the metal removed to provide the slot 17 is bent upwardly, as at 18, at one end of the offset portion 15. The opposite end 19 of the offset portion 15 is provided with a dispensing opening 20.

An inner closure member 21 is illustrated as being in the form of a spring plate which is adapted to fit within the recess defined beneath the outwardly offset portion 15 in the can top 13, when the container is closed. This inner spring closure member seals the openings through the offset portion 15 and is provided at one end thereof with a downwardly curved portion 21a which is adapted to ride over the internal shoulder formed by the adjacent wall portion 16 of the can top when the container is opened.

An outer closure member 22 may be made of Bakelite or other molded substance, and is provided with a transversely extending serrated thumb or finger piece. This outer closure member 22 is adapted to overlie the offset portion 15 on the can top and is provided with a depending boss 23 which is of the same width as the slot 17 and extends into the slot. The inner closure member 21 is secured to the depending boss 23 by a screw 24 or the like, and the boss thus cooperates with the sides of the slot 17 to permit sliding movement of the closure members without relative turning therebetween. To further guard against relative turning between the inner and outer closure members, the inner closure member 21 is provided with an upward projection 25 which is embedded in a corresponding recess in the boss 23 in order to properly locate the closure members relative to one another.

The outer closure member 22 is provided with an internal recess 26 opening toward the slot 17 and of substantially the same width. This recess 26 extends from one edge of the boss 23 toward the upwardly bent portion 18 on the can top 13. The portion 18 is adapted to extend into the recess 26 and is of substantially the same width thereof.

As shown in Figures 1 and 2, a leaf or ribbon spring 28 is disposed in the recess 26 with the ends thereof bearing against the upstanding portion 18 and the opposite end of the recess. The spring 28 thus tends to normally force the closure

members to a closed position, that is, to a position covering the dispensing opening 20.

When it is desired to uncover the dispensing opening 20 so that the contents of the container can be dispensed, pressure is applied to the outer closure 22 against the action of the leaf spring 28. Thus, the inner and outer closure members are moved to the right, as viewed in Figure 2, so that the dispensing opening 20 is uncovered.

- 10 During this movement of the closure members, the downwardly turned portion 21a on the inner spring closure 21 will ride over the internal shoulder provided by the wall portion 16. When pressure is released from the outer closure member 22, the spring 28 which abuts against the outer closure member and the portion 18 on the can top will force both the closure members in the opposite direction for covering the dispensing opening. The spring 28 thus tends to normally maintain the closure members in a closed position. The inner spring closure member 21 serves to maintain both closure members in engagement with the adjacent faces of the offset portion 15. The upwardly projecting portion 18 which extends into the recess 26 serves to prevent rotation of the closure members but permits sliding movement thereof. Likewise, the boss 23 on the outer closure member cooperates with the sides of the slot 17 to guide the closure members 25 in rectilinear movement.

30 In the form of the invention shown in Figures 3 and 4, a coil spring 28a is employed for normally closing the container. As shown in Figure 4, the slot 17a in the offset portion 15a may be 35 narrower than the slot shown in Figures 1 and 2. Similarly, the recess 26a in the outer closure member 22a is slightly narrower so as to snugly house the coil spring. The operation of this 40 form of the invention is substantially the same as that pointed out in connection with Figures 1 and 2. In order to uncover the dispensing opening 20a, pressure is applied to the outer closure member 22a so as to effect movement of both closure members against the action of the coil 45 spring 28a. The downwardly turned edge of the inner spring closure member 21 will ride over the internal shoulder defined by the wall portion 16a. When it is desired to close the container, pressure is released from the outer closure member 22a and the coil spring 28a which abuts against the upwardly projecting portion 18a on the can top will force the closure members to 50 closing position. As in the construction shown in Figures 1 and 2, the upwardly projecting portion 18a and the depending boss 23a prevent relative rotation between the closure members and the can top but permit sliding movement 55 thereof. One edge of the depending boss 23a abuts against the edge of the end 19a of the offset portion 15a to limit closing movement of the closure members.

60 From the foregoing description, it will be seen that a highly efficient dispensing container is herewith provided. The closure is shiftable to an open position against the action of the spring which tends to close and maintain the closure in a position covering and closing the dispensing opening. The closure member is limited in its movement in both directions, and the spring 65 closing means is housed within the outer closure member so that the contents of the container will not come in contact therewith. The inner closure member effectively seals the slot so as to prevent the contents of the container from gaining access 70 to the spring recess in the outer closure member.

75 It is to be clearly understood that various changes in the details of construction and arrangement of parts may be made without departing from the scope of the invention as set forth in the appended claims.

I claim:

1. A dispensing container comprising a body portion, a can top therefor having a dispensing opening, a closure for controlling the dispensing opening, means for slidably mounting said closure on the can top, and spring means housed by said closure for normally maintaining the closure covering the dispensing opening.

2. A dispensing container comprising a body portion, a can top therefor having a dispensing opening, a closure for controlling the dispensing opening and having a recess therein, means for slidably mounting said closure on the can top, and spring means housed within said recess for normally maintaining the closure covering the dispensing opening.

3. A dispensing container comprising a body portion, a can top therefor having a slot and a dispensing opening, a closure for controlling the dispensing opening and having a recess therein, means extending through said slot for slidably mounting said closure on the cover top, and a spring housed within said recess for normally maintaining the closure covering the dispensing opening.

4. A dispensing container comprising a body portion, a can top therefor having a slot and a dispensing opening, an outer closure member overlying the slot and adapted to control the dispensing opening, said outer closure member having a recess therein opening toward said slot, an inner spring closure member underlying the slot and adapted to control the dispensing opening, means extending through said slot for connecting said closure members for sliding movement in unison, and spring means housed within the recess in said outer closure member for normally maintaining both of said closure members covering the dispensing opening.

5. A dispensing container comprising a body portion, a can top therefor having a slot and a dispensing opening, an outer closure member overlying the slot and adapted to control the dispensing opening, said outer closure member having a recess therein opening toward the slot, means providing an upward projection on the can top extending into the recess in said outer closure member, an inner closure member underlying the slot and adapted to control the dispensing opening, means extending through said slot for connecting said closure members for sliding movement in unison, and a spring disposed within said recess and abutting against the outer closure member and the upward projection on the can top for normally maintaining both of said closure members covering the dispensing opening.

6. A dispensing container comprising a body portion, a can top therefor having a slot and a dispensing opening, an outer closure member overlying the slot and adapted to control the dispensing opening, said outer closure member having a recess therein opening toward the slot, an upward projection on the can top at one end of the slot extending into the recess in said outer closure member, an inner closure member underlying the slot and adapted to control the dispensing opening, said outer closure member having a depending boss extending into the slot and substantially the same width thereof for guid-

ing the closure member in rectilinear movement, means connecting said inner closure member to said boss for permitting sliding movement of said closure members in unison, and a spring disposed in said recess and abutting against said outer closure member and the upward projection on the can top for normally maintaining both of said closure members covering the dispensing opening.

0 7. A dispensing container comprising a body portion, a can top therefor having an outwardly offset curved portion, said outwardly offset portion having a dispensing opening at one end thereof and having a longitudinal slot extending toward the opposite end thereof, an outer closure member overlying the slot and adapted to control the dispensing opening, said outer closure member having a recess therein opening toward the slot, means providing an upward projection on said outwardly offset portion extending into the recess in said outer closure member, an inner spring closure member underlying the slot and adapted to control the dispensing opening, means extending through said slot for connecting said closure members for sliding movement in unison, and spring means housed within said recess and abutting against the outer closure member and

the upward projection on the outwardly offset portion for normally maintaining both of said closure members covering the dispensing opening.

8. A dispensing container comprising a body portion, a can top therefor having a slot and a dispensing opening, an outer closure member overlying the slot and adapted to control the dispensing opening, said outer closure member having a recess therein opening toward the slot and a depending boss extending into the slot and of substantially the same width thereof, means providing an upward projection on the can top extending into the recess in said outer closure member, said boss having a recess therein, an inner closure member underlying the slot and adapted to control the dispensing opening, said inner closure member having a projection extending into the recess in said boss for properly positioning both of said closure members relative to one another, means connecting said inner closure member to said boss, and spring means housed within the recess in said outer closure member and abutting against the outer closure member and the upward projection on the can top for normally maintaining both of said closure members covering the dispensing opening.
